UNITED STATES PATENT OFFICE.

EDWIN C. GRIFFIN, OF WEST NEWTON, MASSACHUSETTS.

MILL AND POWER MECHANISM.

SPECIFICATION forming part of Letters Patent No. 449,118, dated March 31, 1891.

Application filed October 29, 1890. Serial No. 369,652. (No model.)

To all whom it may concern:

Be it known that I, EDWIN C. GRIFFIN, a citizen of the Dominion of Canada, residing at West Newton, in the county of Middlesex 5 and State of Massachusetts, have invented certain new and useful Improvements in Mills and Power Mechanisms; and I do hereby declare the following to be a full, clear, and exact description of the invention, such as will 10 enable others skilled in the art to which it app pertains to make and use the same.

My invention relates generally to pulverizing-mills, and particularly to that class thereof in which the reduction or pulveriza- 15 tion of ores and other substances is accom- plished by the revolution of a roll or rolls within and against the inner surface of rings or annular dies, and in which said roll or rolls are held in contact with said rings or 20 annular dies by centrifugal force when the mills are in operation; and it consists in the improvements in the construction, arrangement, and combination of parts disclosed in the following specification.

25 The objects of my invention are the production of a mill in which ores or other substances may be cheaply and rapidly crushed and pulverized or reduced to a powder; to effect the application of the power employed 30 directly to the roll-shaft, whereby the roll will be caused to positively rotate against the annular die, gyrate around the inner surface of the same, and by its rotary momentum and centrifugal force crush and pulverize the ma- 35 terial between the same and said die, and to provide a yielding or universal connection between the driving-power and the roll-shaft, whereby the roll will be positively revolved with its shaft on the same axle and gyrate 40 within and against the inner surface of the annular die. These objects are accomplished by the mechanism illustrated in the accom- 45 panying drawings, forming part of this speci- fication, in which the same reference - nu- mers indicate the same or equivalent parts wherever found throughout the several views, and in which—

Figure 1 represents a central vertical section of a mill provided with my improvement. 50 Fig. 2 represents a top plan view of a portion of my improvement. Fig. 3 represents a horizontal section thereof on the line $x-x$ of

Fig. 1. Figs. 4 and 5 represent details of the construction employed therein. Figs. 6 and 7 represent central vertical sections of 55 modified forms thereof, and Fig. 8 represents a central vertical section at right angles to that shown in Fig. 7.

This invention is an improvement on that for which Letters Patent of the United States 60 were granted to James K. Griffin on August 20, 1889, No. 409,579, and relates particularly to the means for supporting and operating the grinding-roll and roll-shaft shown and de- 65 scribed in said patent, all as hereinafter de- scribed.

Referring to the drawings, the reference- numeral 1 designates the casing of the grind- ing-chamber, and 2 the annular die located therein. This chamber and die, however, 70 may be of any known or preferred construc- tion and constitute no part of this invention, but are shown only for the purpose of illus- trating the operation of the invention claimed herein, which consists of the means employed 75 for supporting the roll-shaft 3 and grinding- roll 4, attached to said shaft, and revolving the roll around the inner surface of the annular die 2.

The numeral 5 represents members of a 80 supporting-frame, preferably of cast-iron, of any desired shape or form, and within the top of these standards are arranged bosses 6, which preferably rest upon inwardly-extending projections 7, formed upon the standards 85 5, and set-screws 8 are employed in connec- tion with the standards for centering or ad- justing the position of the bosses and main- taining them in the desired position. Closely fitting within the bosses 6 is an annular sup- 90 port 9, to which is connected an annular ex- tension 10, having an inwardly-extending flange or rim 11, and connected with exten- sion 10, preferably by a screw-thread, is the hollow conical or cylindrical stud 12, which 95 serves as a support for the wheel or pulley 13 and its attachments. The upwardly-extend- ing conical or cylindrical portion of this sup- port also serves as a bearing or journal upon which the pulley 13 revolves. Many other 100 devices may be employed for making this connection between the standards 5 and the conical support or bearing 12, and the parts 9 and 10 may be formed integral, if preferred.

The wheel or pulley 13 is provided with a hub or journal-box 14, which loosely fits and revolves upon the stud or journal 12. This hub 14 may be formed integral with the pulley 13, or fastened thereto by any suitable means. In the pulley 13, above the hub 14, is a circular opening 16, which is surrounded or inclosed by a casing or boxing 17, as shown in Fig. 2. The hub 14 communicates with the central opening 16, the upper side of which is provided with an annular seat 18, concave on its upper surface, and within or upon this seat rests the ball or sphere 19, firmly attached to the roll-shaft 3. The concave seat, upon which the ball 19 rests, extends slightly above the bottom of the chamber inclosed by the casing 17, and on opposite sides of the ball within the casing are formed recesses 20, having vertical plane side faces 21, parallel to a vertical plane through the center of the pulley. In these recesses work cylindrical journals or trunnions formed on or firmly attached to the ball or sphere 19, and between the vertical surfaces of the recesses or boxes 20 and the journals or trunnions 22 on the driving or pressure side thereof, as the case may be, and preferably loosely placed, are gibbs 23, plain on the side adjoining the vertical surfaces of the recesses and cylindrically concave on the other to fit the trunnions or journals 22. The casing 17 is provided with a cover 24, the top of which contains a chamber 25, into which oil or other lubricants are poured through openings provided for this purpose, from which they pass into the recesses or journal-boxes 20 and onto the ball 19 through passages 26.

In Fig. 6 I have shown means for preventing the upward movement of the roll-shaft 40 and roll, (a tendency to which exists in this class of mills,) consisting of a ring or cap 27, the lower surface of which fits upon the upper surface of the ball 19, held in place by a screw-bolt 28, provided with a head 29 and nut 30, and in Figs. 7 and 8 a spiral spring 31 is inserted between the head of the bolt 28 and the ring or cap 27. This form of construction is preferable in some respects to that shown in Fig. 6, in that it admits of greater ease of movement of the ball 19 and roll-shaft and produces less friction.

With the construction described, when the pulley 13 is revolved by a belt or otherwise, rotary motion is thereby imparted to the roll-shaft and grinding or pulverizing roll 4 attached thereto, by means of the journals or trunnions 22, and it will be seen that the roll-shaft supported by the ball 19 has perfect freedom of motion at all times to swing in any direction without impeding or interfering with its rotary motion, the device by which the shaft is supported constituting a perfect universal joint.

Where the hub 14 and stud 12 are made conical, as described, the wear caused by friction may be taken up by means of the screw connection between the stud and its annular

support 10, and if it is desired to obtain vertical adjustment of the roll-shaft and its attachment it may be had by means of the screw 70 connecting the parts 9 and 10, and it is evident that the entire support for the roll-shaft, including the pulley, may be adjusted laterally, leveled, and secured by the set-screws 8 and studs 6. It is also evident that a toothed 75 wheel or pulley or a wheel driven by any device other than a belt may be substituted for the pulley 13 without departing from the principle of my invention; also, that the hub 14 may be made to fit and revolve within the 80 hollow stud 12, instead of around it, as herein shown and described.

If desired, the shaft 3 may be held by journal-bearing or otherwise in constant alignment at an angle to the axis of motion of the 85 pulley by reason of the fact that the coupling forming the connection between the shaft and pulley constitutes a universal joint, and instead of the form of coupling or joint herein described any other form of universal 90 coupling may be employed without departing from the scope of my invention, so far as it relates to the combined wheel or pulley and roll-shaft connected by a universal coupling, whereby the roll-shaft and roll attached 95 thereto have perfect freedom to swing in any direction without impeding or interfering with its rotary motion, and whereby when the pulley is revolved the roll-shaft and roll are given a radial rotary movement and the roll-shaft and roll are gyrated around the central axis of the mill, the roll being held in contact with the annular die in the grinding-chamber, when the mill is in operation, by 100 centrifugal force, and falling away from said die, when the mill is not in operation, by 105 gravity.

In operation the roll 4 is rotated around the die 2 by means of a positive rotary power applied to the shaft, and is held in contact with or pressed against the die by centrifugal force.

The material to be pulverized is introduced within the grinding-chamber by means of a 115 spout 32, or in any other desired manner, and is taken up by the plows or stirrers 33, attached to the bottom of the roll, and is thrown against the annular die, where it is operated upon and crushed or ground by the roll 4, and this operation is repeated until the material 120 has been reduced to the required degree of fineness, when it is discharged through the screen 34 into the annular chamber 35 between the screen and casing 1, from which it passes into a receptacle or hopper 36 by means 125 of passages 37, formed in the annular base of the mill, from which it is removed by a conveyor 38. The operation of discharging the pulverized material through the screen 33 is 130 greatly facilitated by fans or vanes 39, attached to the roll-shaft immediately above the roll, in connection with the stirrers or plows 32, as they operate to cause a circulation of air through the mill and force the air,

together with the pulverized material, out through the screen into the chamber 34. The air is drawn into the mill in small quantities through the top thereof by the fans or vanes, 5 which thus also operate to keep all dust or pulverized material within the mill. This feature of construction, however, constitutes no part of the invention claimed herein.

It is evident that many changes may be 10 made in the construction, combination, and arrangement of the various elements of the invention described herein without departing from the scope thereof, and I do not limit myself to the exact form shown, and it is also 15 evident that the power mechanism, consisting of the pulley, the roll-shaft, and means by which they are coupled or connected, which constitutes the main feature of my invention, is applicable to many uses other than that in 20 connection with which it is here illustrated and described.

Having fully described my invention, its construction and operation, I claim, and desire to secure by Letters Patent, the following:

25 1. The combination, in a mill, of an annular die located in the grinding-chamber, a pulley supported horizontally above the grinding-chamber, and a roll-shaft and roll suspended from the pulley and directly connected therewith by means of a universal coupling, whereby the roll-shaft and roll are at liberty 30 to swing in any direction, and when the pulley is revolved the roll is carried or rotated around the annular die and held in contact 35 therewith by centrifugal force, substantially as shown and described.

2. In a pulverizing-mill, the combination of an annular die located in the pulverizing-chamber, a pulley supported horizontally 40 above the grinding-chamber, and a radially-movable roller-shaft and roll suspended therefrom on a line with the axis thereof and directly connected therewith by a universal coupling, whereby when the pulley is revolved the roll is gyrated around the annular 45 die and held in contact therewith by centrifugal force, substantially as shown and described.

3. In a pulverizing-mill, the combination, 50 with an annular die, of a radially-movable roll-shaft and roll, and a pulley from which the roll-shaft is suspended on a line with its axis, the pulley and roll-shaft being connected by a universal joint or coupling, substantially as 55 shown and described.

4. In a pulverizing-mill, the combination of an annular die located in the pulverizing-chamber, a pulley arranged horizontally above 60 said grinding-chamber, provided with a central opening and recesses at the sides thereof, a radially-movable roll-shaft extending through said opening and provided with journals or trunnions adapted to enter said recesses, and a roll mounted on the roll-shaft, 65 substantially as shown and described.

5. In a pulverizing-mill, the combination of an annular die located in the pulverizing-

chamber, a pulley mounted horizontally above said chamber, provided with a central opening and recesses on opposite sides thereof, a 70 radially-movable shaft, as 3, provided with a ball or sphere having journals or trunnions on its opposite sides adapted to enter the recesses, an annular ring or bearing on which the sphere rests and by which it is supported, 75 and a roll mounted on the radially-movable shaft and adapted to travel around the annular die, substantially as shown and described.

6. In a mill, the combination, with the supports 5, of the hollow supporting stud or sleeve 12, connected with said supports 5, the pulley provided with the conical or cylindrical hub 14, revolvably mounted on said stud, and the roll-shaft suspended from the pulley 85 by means of a universal coupling, substantially as shown and described.

7. The combination, in a pulverizing-mill, of the annular die located in the grinding-chamber, the supports 5, the hollow support 90 12, adjustably connected with said support, the pulley revolvably mounted on said stud, and the roll-shaft and roll, the former of which is suspended from said pulley on a line with its axis and connected therewith by a universal joint or coupling, substantially as shown and described.

8. In a mill, the combination, with an annular die located in the grinding-chamber, of a pulley revolvably mounted above the grinding-chamber, and a radially-movable roll-shaft and roll suspended from said pulley on a line with its axis and connected directly therewith by a universal coupling, substantially as shown and described. 105

9. In a mill, the combination, with an annular die, of a pulley revolvably mounted above the die, and a radially-movable roll-shaft and roll suspended from said pulley and connected directly therewith by a universal coupling, the pulley being vertically adjustable on its supports, substantially as shown and described. 110

10. In a mill, the combination, with an annular die, of a pulley revolvably mounted 115 above the die, and a roll-shaft and roll suspended from said pulley and connected therewith by a universal coupling, the pulley being laterally and vertically adjustable on its supports, substantially as shown and described. 120

11. The combination of the pulley 13, having the central opening 16 and journal-box casing 17, the recesses within which are provided with vertical side walls forming journal-bearings, with the shaft 3, having the ball 19, provided with the journals 22, substantially as shown and described. 125

12. The combination of the pulley 13, having the journal-box casing 17 and central 130 opening, with the shaft 3 extending through said opening, provided with the ball 19 and trunnions or journals on opposite sides thereof, an annular concave seat on which said

ball rests, an annular ring or cap 27 resting upon said ball, and means for holding the ring or cap in position, substantially as shown and described.

- 5 13. The combination of the pulley 13, having the journal-box casing 17 and central opening, with the shaft 3 extending through said opening, provided with the ball 19 and trunnions or journals on opposite sides thereof, of, an annular concave seat on which said ball rests, an annular ring or cap 27 resting on said ball, and means for exerting a yielding pressure on the cap or ring, substantially as shown and described.
- 10 14. The combination of the pulley 13, having the central opening 16, and recesses 20, of the shaft 3, provided with the ball 19, and journals 22 and gibbs 23, substantially as shown and described.
- 15 15. The combination of the pulley 13, having the recesses 20, with the shaft 3, provided with the ball 19, having the journals adapted to enter the recesses, a cap or ring 27, adapted to seat upon the ball, and means for holding it in contact therewith independent of the means by which the shaft and ball are supported, substantially as shown and described.

16. In a mill, the combination, with an annular die located in the grinding-chamber, of a pulley revolvably mounted above the 30 grinding-chamber, a radially-movably roll-shaft and roll suspended from said pulley and connected therewith by a universal coupling, and means for preventing the elevation or lifting of the roll-shaft when the mill is in 35 operation, substantially as shown and described.

17. In a mill, the combination of the annular die, the supports 5, the bosses 6, the annular rings or supports 9 and 10, the stud or 40 sleeve 12, and the pulley revolvably mounted on said stud and the roll shaft and roll connected with said pulley by a universal coupling, substantially as shown and described.

18. The combination, with the hollow stud 45 12, of the pulley 13, revolvably mounted thereon, and the radially-movable shaft 3, connected with said pulley by a universal coupling, substantially as shown and described.

EDWIN C. GRIFFIN.
